US0D1006866S

(12) **United States Design Patent** (10) **Patent No.:** **US D1,006,866 S**
(45) **Date of Patent:** **** Dec. 5, 2023**

(54) **SMART GLASSES**

(71) Applicant: **Falcon Innovations Technology (Shenzhen) Co., Ltd**, Shenzhen (CN)

(72) Inventors: **Bin Zheng**, Shenzhen (CN); **Mingjie Wang**, Shenzhen (CN)

(73) Assignee: **Falcon Innovations Technology (Shenzhen) Co., Ltd.**, Shenzhen (CN)

(**) Term: **15 Years**

(21) Appl. No.: **35/515,310**

(22) Filed: **Sep. 19, 2022**

(80) **Hague Agreement Data**

Int. Filing Date: **Sep. 19, 2022**

Int. Reg. No.: **DM/223679**

Int. Reg. Date: **Sep. 19, 2022**

Int. Reg. Pub. Date: **Oct. 7, 2022**

(30) **Foreign Application Priority Data**

Aug. 18, 2022 (CN) 202230540985.2

(51) **LOC (14) Cl.** **16-06**

(52) **U.S. Cl.**

USPC **D16/309**; D14/372

(57)

CLAIM

The ornamental design for smart glasses, as shown and described.

DESCRIPTION

1. Smart glasses

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

The design is smart glasses used for augmented reality technology; figs. 1.1-1.10 are drawings showing an embodiment of the smart glasses.

1 Claim, 10 Drawing Sheets
